UNITED STATES PATENT OFFICE.

WILLIAM LESLIE BEALL, OF CHATTANOOGA, TENNESSEE, ASSIGNOR TO INTERNATIONAL HARVESTER COMPANY, OF CHICAGO, ILLINOIS, A CORPORATION OF NEW JERSEY.

MOLDBOARD.

Application filed September 4, 1924 Serial No. 735,736.

This invention relates to cast metal plow moldboards of the kind having a chilled face or working surface and a comparatively soft metal back.

5 The objects of the invention are to provide against the warping strains which tend to crack or break the moldboard during the cooling process and to make possible the production of a harder chill on the surface of 10 the moldboard; also to give the moldboard the required strength while economizing in the amount of metal used in its construction. These objects have been attained by forming the rear or under side of the moldboard in 15 a novel manner including an arrangement of ribs and grooves extending longitudinally of the board, as hereinafter more particularly described and claimed.

In the accompanying drawings,—

20 Fig. 1 is a back view of a moldboard embodying the improved features of construction comprising the invention; and

Fig. 2 is a section on line 2—2 of Fig. 1.

The moldboard illustrated is of conventional form and has two angularly related forward edges 5 and 6 adapted to engage the shin and blade of the plow-point or share, which edges will be hereinafter referred to as the connecting edges of the moldboard, and 30 upper and lower longitudinal or free edges 7 and 8 which come together in the rounded end of the moldboard 9. The usual openings for attaching bolts are shown at 10.

In the preferred form of the invention, the 35 under side of the moldboard is fitted with a succession of closely spaced grooves 11 which separate ridges 12 of substantially the same width as the grooves. The grooves originate or begin adjacent the connecting edges 5 and 40 6 of the moldboard. The three lower grooves begin adjacent the lower end of the share engaging edge of the board as at 13, while the remaining grooves begin adjacent the shin engaging edge 5. Certain of these grooves, 45 indicated at 14, run parallel to the share engaging edge 6 down to the point of origin of grooves 13, after which they continue parallel thereto. The arrangement of the grooves is such that they extend longitudinally of the board in parallel relation to each other and to the upper and lower free edges thereof merging in the longitudinal median line of the moldboard, as clearly illustrated in Fig. 1. As an additional reinforcing element the lower longitudinal free edge of the

moldboard is preferably formed with a rearwardly projecting marginal flange 15, as shown in Fig. 2.

This provides a construction in which the entire area of the under side of the moldboard is formed with longitudinally extending alternate grooves and ridges which conform to the contour of the longitudinal edges of the moldboard, the thickness of such a board when measured through the ridges being no greater than that of an old type of moldboard having a plain back. Thus it will be seen that a board formed according to the invention herein disclosed will be lighter or composed of less metal than a similar board 70 of the old type, resulting in economy of manufacture without sacrifice of strength, as it has been found that the strains tending to crack a moldboard during cooling will act transversely across the board and, forming and 75 arranging grooves on the back of the board in the manner herein described, will effectively resist the action of such strains while permitting employment of less metal as above stated. As a large proportion of the area of 80 the moldboard (that occupied by the grooves) is thinner than in the case of moldboards made of uniform thickness, the face of the board will take a harder chill and be correspondingly more efficient in scouring. 85

While the specific arrangement of grooves above described represents the preferred embodiment of the invention, it will be evident to those skilled in the art that certain variations from the pattern shown may be made 90 without departing from the gist of the invention as defined in the following claims.

What is claimed is:

1. A cast metal moldboard having its rear or under side formed with a plurality of longitudinally extending grooves, said grooves being formed in series paralleling the free edges thereof. 95

2. A cast metal moldboard having its rear or under side formed with a plurality of longitudinally extending grooves paralleling the free edges thereof and merging in its longitudinal median line. 100

3. A cast metal moldboard having its rear or underside formed with a succession of parallel grooves conforming to the contour of the free edges thereof, said grooves originating adjacent the connecting edges of the moldboard. 105

4. A cast metal moldboard having the en- 110

tire area of its rear or underside formed with a succession of closely spaced parallel grooves conforming to the contour of the free edges thereof, said grooves originating 5 adjacent the connecting edges of the moldboard and merging at its longitudinal median line.

5. A cast metal moldboard having two angularly related connecting edges and longitudinal free edges merging into a rounded 10 upper end, and having its rear or under side formed with successive closely spaced continuous parallel grooves running parallel to the free edges of the moldboard and merging 15 at its longitudinal median line, the grooves originating adjacent said connecting edges and certain of said grooves running parallel to one connecting edge.

6. A cast metal mold board having its rear 20 or under side formed with a succession of parallel longitudinal extending grooves and with a marginal flange projecting rearwardly from its lower longitudinal free edge.

7. A cast metal moldboard having two series of substantially parallel continuous ribs 25

on its under side, corresponding ribs of the separate series diverging forwardly from positions near the longitudinal median line of the moldboard.

8. A moldboard, an upper series of ribs 30 substantially parallel to each other and to the upper free edge of the moldboard, and a lower series of ribs substantially parallel to each other and to the lower free edge of the moldboard, the ribs of the upper series meeting the ribs of the lower series at positions which are substantially aligned and in the vertical median line of the moldboard.

9. A moldboard having its under surface provided with a plurality of pairs of forwardly diverging continuous ribs.

10. A moldboard having its under surface provided with a plurality of series of substantially parallel ribs, the ribs of the separate series being substantially parallel to 45 lines which diverge forwardly of the moldboard.

In testimony whereof I affix my signature.

WILLIAM LESLIE BEALL.
